UNITED STATES PATENT OFFICE.

WILLIAM J. RUFF, OF QUINCY, ILLINOIS.

VAPOR-FILTER.

1,387,870.

Specification of Letters Patent. Patented Aug. 16, 1921.

Application filed June 21, 1916. Serial No. 104,870.

To all whom it may concern:

Be it known that I, WILLIAM J. RUFF, a citizen of the United States, residing at Quincy, in the county of Adams and State 5 of Illinois, have invented a certain new and useful Vapor-Filter, of which the following is a specification.

This invention relates to a process for mechanically separating alcohol from various 10 beverages, especially from beer, and to the apparatus for carrying out the process. The invention is exemplified in the combination and arrangement of parts shown in the accompanying drawings and 15 described in the following specification, and in the steps of the process described in the specification and carried out in connection with the mechanism shown in the drawings, and it is more particularly pointed out in 20 the appended claims.

In the drawings, Figure 1 is a somewhat diagrammatical elevational view with parts in section, of one form of mechanism constituting part of the present invention, and 25 Fig. 2 is a vertical sectional view showing more in detail a portion of the mechanism illustrated in Fig. 1.

Referring to the figures of the drawings, the numeral 1 designates generally a receptacle or tank preferably made of steel and 30 having its interior portion entirely coated with glass enamel or other material which is not in any way affected by the beverages which are operated upon and which therefore 35 will not injure the beverages as would the unprotected metal surface. The receptacle must be made of strong material to resist pressures to which it is subjected, and for this reason the main body of the walls 40 of the receptacle are preferably made of steel. As shown most clearly in Fig. 2, a second receptacle 2 is mounted upon the receptacle 1 and is connected therewith by a communicating passage 3. The receptacle 45 2 is constructed of materials similar to those of receptacle 1. Within the receptacle 1 is an attemperating coil 4 which may be made of copper and which may, if found desirable, be exteriorly plated with tin or silver 50 to prevent any contamination of the liquid in the receptacle by contact with the copper pipe. Ordinarily, however, this plating will not be necessary as copper itself is not affected by most beverages operated upon 55 by the process to be described. The attemperating coil 4 is provided with communi-

cating pipes 5 and 6 which may be connected selectively with sources of heating and cooling media. The receptacle is provided with a thermometer 7 to indicate the temperature 60 of the liquid within the tank and with a pressure gage 8 arranged to indicate pressures below and above atmosphere. A glass gage 9 is provided to indicate the height of 65 liquid within the tank.

Within the receptacle 2 is a series of plates 10 which are curved upwardly at their outer edges and are substantially the same diameter as the interior of the receptacle. The plates 10 are supported centrally by a column of supporting cylinders 11 which rest 70 one upon another as indicated in the drawing. The column is carried by a spider 12 supported at the bottom portion of the tank 2. Alternating with the plates 10 is a second 75 series of plates 13 which are supported centrally in a way similar to the plates 10 but which are curved downwardly at their peripheries and which are of smaller diameter than the interior of the tank. The edges of 80 the plates 13 are positioned slightly below the edges of the plates 10 so that liquid flowing from the periphery of the plates 13 will be intercepted by the plates 10 and carried 85 inwardly toward the center of the receptacle. A series of openings 14 is provided near the centers of the plates 10 to permit liquid to flow from the plates 10 onto the tops of 90 the plates 13. An upright pipe 15 extends through the center of the cylinders 11 forming a support for the cylinders and also providing a conduit extending upwardly through their center. A spider 16 is secured to the upper end of the pipe 15 at a position 95 above the uppermost plate 13, and a curved deflector 17 is carried by the spider 16 for the purpose of directing fluid discharged from the upper end of the pipe 15 downwardly onto the upper plate 13. The pipe 15 extends downwardly through the central 100 portion of the tank 1 and extends outwardly through the wall of the chamber 1 as indicated at 18. A pipe 19 communicates with the tank 1 through the bottom thereof as shown in the figures of the drawings, and 105 both pipes 18 and 19 are connected with a circulation pump 20. By this construction liquid in the tanks 1 and 2 may be caused to circulate through pipe 15 and in the tank 1 the liquid being drawn from the bottom of 110 the tank by the pipe 19 and forced upwardly through the pipe 15 and discharged at the

upper end thereof against the deflector 17. Within the tank 2 beneath the lowermost plate 13 is a distributing head or ring 21 provided with a series of perforations and connected with pipes 22 and 23 which communicate respectively with sources of air and carbon dioxid under pressure. The pipes 22 and 23 are provided with valves 24 and 25 to control admission of gases therefrom. All of the parts within the tank 2 are covered in a way similar to those in tank 1 to prevent metal turbidity in the beverage. Near the upper portion of the tank 2 a pair of sight glasses 26 is provided, arranged opposite one another so that the operator may look through the tank from one glass to the other to observe the condition of the contents; instead of providing two glasses a fixed electric light may be placed within the tank 2 and used in conjunction with a single glass, or such a light may be used in conjunction with a pair of glasses, if found desirable. An adjustable blowoff valve 27 is connected with the upper portion of the tank 2 and arranged to be set to permit escape of compressed gases within the tank at various pressures under the control of the operator. A pipe 28 is connected with the upper portion of the tank 2 and a bypass 29 is provided in this pipe having a valve 30 by which communication may be established between the pipe 28 and the outer atmosphere. The pipe 28, as shown in Fig. 1, leads to a separating chamber 31. This chamber is provided with a drain pipe 32 which leads from the lower portion of the chamber and connects with the tank 2 near the bottom portion of this tank. A second outlet pipe 33 communicates with the interior of the chamber 31 near the upper portion of the chamber and the mouth of this pipe is surrounded by a smaller chamber 34 which communicates with the larger chamber 31 through a block of porous material 35 such as porous earthware, through which gas will readily pass but which resists the passage of liquid. Located in the upper portion of the chamber 31 is a sprinkler head 36 arranged to spray the interior of the chamber with liquid. This sprinkler head is connected by a pipe 37 with the discharge end of the pump 20 and is controlled by a valve 38 located in the pipe 37. The chamber 31 is provided with a pair of sight glasses 39 similar to those in the chamber 2.

The pipe 33 leads to a double pipe cooler of well known construction indicated at 40 in Fig. 1 of the drawing. The pipe 33 is connected with the exterior portion of the double pipe cooler while the interior coil 41 of the cooler communicates with a source of cooling liquid such as salt brine. An outlet pipe 42 from the outer portion of the cooler 40 leads to a collection tank having an upper chamber 43 and a lower chamber

44. The pipe 42 leads to a point slightly above the separating wall 45 between the two chambers, and liquid in the chamber 43 is trapped into the chamber 44 by a siphon 46 which has its intake end located just 70 above the division wall 45. A pressure equalizing pipe 47 has one end located near the lower portion of the chamber 43 and the other end communicating with the upper portion of the chamber 44, as indicated 75 in the drawing. A vacuum pump 48 is connected by a pipe 49 with the upper portion of the chamber 43 and is provided with a discharge pipe 50 communicating with the lower portion of a trap 51 partially filled 80 with distilled water and provided with an outlet pipe 52 at its upper end.

In carrying out the process, the beer or other liquid to be dealcoholized, is placed in the tank 1, the tank being filled preferably 85 to a position approximately that indicated by the broken line 53 in Fig. 2 of the drawings. In dealcoholizing beer, the completely finished beer, ready for the market, is used. In this respect this process differs from the 90 process of manufacturing so-called temperance beers, in which the process of fermentation is stopped before it is complete to prevent the formation of the usual amount of alcohol, and in which the alcohol that is 95 formed is boiled off. Where completely finished beer is employed, the flavor and food value of the beer is entirely retained and the only effect of the process is to remove the alcohol. The result which is obtained occupies a position relative to beer as now manufactured, similar to that occupied by grape juice relative to wine. When the tank 1 has been filled, a heating medium is admitted to the attemperating coil 4 and the pump 20 105 is started to cause circulation of the liquid in the tank. The liquid is pumped from the bottom of the tank 1 through the pump 20 and upwardly through the pipe 15, where it is discharged against the downwardly 110 curved deflector 17. This deflector directs the beer onto the upper surface of the plate 13 over which it flows downwardly and outwardly in all directions and falls from the periphery of the plate 13 in a thin film-like 115 sheet onto the plate 14 below. The liquid then flows to the center of the plate 10, emerges through the openings 14, and again flows over the next lower plate 13 and falls in a miniature cataract from this plate in 120 the same way as it did from the plate 13 above. This process is repeated as many times as there are plates in the tank 2, the liquid finally emerging at the lower portion 125 of the tank and returning through the passage 3 into the tank 1. In this way the liquid is given complete circulation through the tanks and is uniformly heated by the coil 4. When the liquid has been thus heated, warm dehydrated air under pressure 130

is admitted through the pipe 23 and the distributing ring 21, and the bypass 29 is opened by the valve 30 to permit escape of this air from the upper portion of the chamber 2. As the air passes upwardly through the chamber 2, it obviously must pass through the film of beer falling from the peripheries of the plates 13. As it thus passes upwardly through the chamber 2, the air carries away with it the carbon-dioxide with which the finished beer is charged during its manufacture. The air and the carbon-dioxide pass out through the bypass 29 into the atmosphere. As the beer is circulated by the pump 20, every portion of the beer will in a short time be subjected to the action of the uprising air in the chamber 2 and thus the entire amount of beer in the tank 1 will be freed from its charge of carbon-dioxide gas. This separation of carbon-dioxide from the beer by the passage of air through the liquid, is the more readily accomplished because of the fact that the temperature of the beer has been raised by the attemperating coil 4. The principal reason for thus freeing the beer of carbon-dioxide is to prevent foaming during further steps of the process. After this step of the process is completed, the valve 30 is closed, as well as the valve 25 in the pipe 23, and the exhaust pump 48 is started. The circulation pump 20 is kept in operation and the beer continues to circulate through the tanks in the manner previously described. The shape of the deflector 17 and of the plates in the tank 2, is such that they very much reduce the tendency of the beer to foam in the tank. As the beer strikes the deflector 17, it is directed downwardly in a comparatively thin sheet at the periphery of the deflector, and flows in a film over the surface of the different plates. This filmy flow of the beer tends to break up the foam forming bubbles and hence decreases the tendency to foam within the tank. The convex upper surface of the plate 13 insures a uniform flow of the liquid in all directions from the center of the tank, so that it will fall from the periphery of the plates at all sides thereof. Any tendency to foam within the tank 2 may be readily detected by means of the sight glasses 26 and the conditions which cause the foaming can then be remedied.

As the heated liquid is circulated and flows in a film-like stream over the surface of the plates 13, and falls in a similar stream from the periphery of the plates, the pressure in the receptacle 2 is reduced by the suction from the exhaust pump 48 and the alcohol in the beer or other liquid is thus caused to evaporate and pass upwardly from the receptacle 2 through the pipe 28 into the separating chamber 31. The liquid in the tanks is maintained at a temperature between the boiling points of alcohol and water at the

particular pressure produced in the tanks by the pump 48. A considerable range of pressures and temperatures may be employed, the essential features being that the temperature shall be kept comparatively low to prevent producing any change in the composition of the constituents of the liquid, but that the temperature shall be such at the pressure maintained, that the greatest amount of alcohol will be evaporated in a given time without carrying over therewith any considerable amount of water. It is found advantageous to maintain the pressure as low as can be practically done with commercial apparatus, in order that the evaporation process can be carried on at a comparatively low temperature. This insures against change in the composition of the beer and also helps to avoid the formation of foam. The most practical pressure has been found to be about 28 to 30 inches vacuum with a temperature approximately 90° Fahrenheit. Of course these values may be considerably varied, the maximum operable temperature being about 115°. It is essential that the temperature shall be kept below the coagulation point of the albuminous constituents of the beer.

The vapor drawn from the tank 2, notwithstanding the fact that the temperature in the tank is below the boiling point of water, will carry over with it a certain amount of water vapor along with the alcohol vapor. It is desirable to return the same water to the beer that passes off with this vapor in order that the consistency of the beer may not be changed by the removal of water, and in order that the flavor may not be altered by the addition of water not originally forming a part of the liquid. In order that the water vapor may be separated from the alcoholic vapor and returned to the tank, the separating chamber 31 is provided, which is maintained at approximately the temperature of the surrounding atmosphere. The reduced temperature in the separating chamber 31 will cause the water to be condensed and collected in the bottom of the chamber from whence it will be conducted through the pipe 32 back into the tank 1. The alcoholic vapor, which is more volatile than the water vapor, passes on through the pipe 23 toward the exhaust pump 48. To reach the pipe 33, however, the alcoholic vapor must pass through the filter 35 which, as explained, is of porous clay and will therefore arrest particles of moisture which attempt to pass into the pipe 33. If at any time it is observed that foam has formed in the separating chamber 31, this may be readily removed by opening the valve 38 and causing a spray of liquid from the pump 20 to be forced through the pipe 37 into the chamber, thus washing out any foam in the chamber and carrying it down through the pipe 32.

into the tank 1. The alcoholic vapor passes from the chamber 31 into the double pipe cooler 40 where it is subjected to a low temperature and immediately condensed into liquid form. The liquid alcohol passes downwardly through the pipe 42 into the upper tank 43 of the collection chamber. In order that the alcohol may not be continuously subjected to the evaporating influence 10 of the exhaust pump 38, it is immediately trapped from the tank 43 into the lower tank 44 by means of the siphon 46. The pipe 47 is arranged to maintain equilibrium of pressure in the two tanks. A small amount of 15 alcohol may be retained in suspension in the gases, carbon-dioxid and air which pass through the pipe 49 to the exhaust pump 48, and in order that no alcohol may be wasted, the exhaust of the pump is passed through a 20 second chamber 41 which contains distilled water in which the residuary alcoholic vapor will be retained in solution, thus preventing any loss of the by-product alcohol. By continuing the process described for a sufficient 25 time, all of the beer in the receptacle 1 will be submitted to the evaporating action of the increased temperature and reduced pressure, and thus practically all of the alcohol in the beer can be removed. It has been 30 found that beer subjected to the process retains not more than one half of 1% of the alcohol originally in the beer.

After the alcohol has thus been removed, all of the openings leading to the tanks 1 35 and 2 are closed except those from the pump 20, and the inlets to the attemperating coil 4. The heating medium is then shut off from the coil 4 and a cooling medium is circulated through the coil in its place. The pump 20 40 continues to circulate the liquid in the two tanks and the cooling medium is passed through the coil 4 until the temperature of the liquid in the tanks is reduced as near to freezing point as is practical without actually freezing any of the liquid. A temperature of about 34° is found to be desirable. When the temperature of the beer has been 45 thus reduced, the valve 25 is opened to permit carbon-dioxid gas under pressure to enter the chamber 2. The pressure of the carbon-dioxid used is preferably about 30 pounds per square inch and the blowoff valve 27 is set to regulate this pressure to the desired amount. During the recarbonation 50 process the circulation of the beer is maintained in order to make certain that all of the beer in the tank shall be subjected to the process. After a period, the pressure in the tanks is gradually reduced to the pressure to 55 which beer is usually subjected when placed in bottles or kegs preparatory to shipment. Before the beer is bottled, however, a sufficient amount of distilled water is added to raise the level of the liquid in the tank 1 60 to that which it occupied at the beginning

of the process, that is enough distilled water is added to take the place of the alcohol and moisture removed from the beer. After this has been done, the beer may be drawn off, 70 filtered, and then bottled in the usual way, or it may be placed in kegs and shipped to the trade.

I claim:

1. A dealcoholizing device comprising a receptacle having a drain opening in its bottom and inlet and discharge openings directed toward each other in the sides thereof; a filter over the discharge opening; a source of alcoholic and other vapors connected with the inlet opening; and means for moving 75 said vapors from the inlet opening directly against said filter, the latter being adapted to permit the passage of alcoholic vapor and arresting the passage of other vapors there-through.

2. A dealcoholizing device comprising a receptacle having a drain opening in its bottom and inlet and discharge openings directed toward each other in the sides thereof; a filter over the discharge opening; a source of 90 alcoholic and other vapors connected with the inlet opening; means for moving said vapors from the inlet opening directly against said filter, the latter being adapted to permit the passage of alcoholic vapor and 95 arresting the passage of other vapors there-through; and means for removing foam from the front of said filter.

3. A dealcoholizing device comprising a container for beverages; means in said container for separating alcoholic and other vapors from beverages in said container; a receptacle having a discharge opening in one side thereof; a filter over said discharge opening; a pipe connecting the top of said 100 container with the side of said receptacle and opening directly toward said filter; and an exhaust pump connected with said discharge opening and adapted to draw vapors directly from said pipe against said filter. 105

4. A dealcoholizing device comprising a container for beverages; means in said container for separating alcoholic and other vapors from beverages in said container; a receptacle having a discharge opening in one side thereof; a filter over said discharge opening; a pipe connecting the top of said 110 container with the side of said receptacle and opening directly toward said filter; an exhaust pump connected with said discharge 115 opening and adapted to draw vapors directly from said pipe against said filter; a sprinkler head in and having its size and shape substantially fitting the top portion of said receptacle and disposed above said filter; and a pump having its discharge opening connected with said sprinkler and its suction opening connected with the lower part of 120 said receptacle. 125

5. Dealcoholizing apparatus comprising a 130

receptacle with a drain opening in its lower side and inlet and discharge openings considerably above the drain opening; a source of alcohol and other vapors connected with 5 said inlet opening; a filter closing said outlet opening and adapted to permit the passage of alcohol and arrest the passage of said other vapors; an exhaust means connected with said exhaust opening; and a spray at 10 the top of the receptacle adapted to wash foam from the inner walls of the receptacle

and the side of the filter away from said exhaust opening.

In testimony whereof I have signed my name to this specification, in the presence of 15 two subscribing witnesses, on this 14th day of June, A. D. 1916.

WILLIAM J. RUFF.
